UNITED STATES PATENT OFFICE.

HAROLD HALE, OF HARROW, ENGLAND.

COOLING DEVICE.

1,076,421.

Specification of Letters Patent.

Patented Oct. 21, 1913.

Application filed September 16, 1912. Serial No. 720,486.

To all whom it may concern:

Be it known that I, HAROLD HALE, a subject of His Majesty the King of Great Britain, residing at 40 Sheepcote road, Harrow, Middlesex, England, engineer, have invented certain new and useful Improvements in Cooling Devices; and I do hereby declare the following to be a full, clear, and exact description of the invention, such as will enable others skilled in the art to which it appertains to make and use the same.

This invention relates to improvements in coolers of that type wherein a revoluble carrier for the goods is arranged within the cooler casing, so that by rotating the carrier the desired goods may be brought opposite to a door in the casing and easily removed. These carriers have been arranged to rotate in some cases about vertical axes and in others about horizontal axes, and have been furnished with means, such as bottle holders and removable receptacles, for conveniently holding the goods, but hitherto the door for the removal of the goods has been located in the side of the casing. As a result, each time this door has to be opened some of the cold air descends through it from the casing and warmer exterior air ascends and enters the casing through it, slightly raising the temperature within the casing.

According to my invention which is directed to the preservation of a low temperature combined with easy access to the contents, I dispense with all doors in the sides of the casing, and arrange a door or trap just sufficiently large for easy removal of the contained articles in the top thereof, and as a result, since the warmer air will not descend nor the cold air ascend, this door may be repeatedly opened without appreciably raising the temperature within the refrigerator.

The ice boxes, brine coils, or the like, would preferably be disposed surrounding the revoluble carrier, as within the angles of the casing for example, when the latter is rectangular. By such a disposition of the refrigerant a better effect is obtained than when the same is disposed centrally of the carrier, or on one side thereof only, as has hitherto been the case in coolers of this type.

Although in the following description of the drawings I shall by way of example describe my invention as applied to a cooler for wine, its application is not limited there-

to, since with suitable modifications the revoluble carriers may obviously be adapted for the reception of articles and goods of all descriptions.

Referring to the annexed drawings:—Fig. 60

Fig. 1 shows a cooler embodying my invention in sectional elevation. Fig. 2 is a plan view, and, Fig. 3 is a sectional plan of Fig. 1.

a is the cooler casing, whereof the walls, 65

bottom and top lid proper *b*, are made hollow and packed with insulating material in the usual manner.

c is a small hinged door or trap in the top lid proper. 70

The revoluble carrier, which is here shown as specially adapted for bottles, though its construction may as before stated be modified to accommodate any goods required, comprises the vertical shaft *d* rotatable in 75 a bearing in the cross piece *e* and in the bearing *f*, said shaft having keyed to its lower end a boss from which extend the radial arms *g* whose outer ends are connected by a flanged ring *h* within which 80 ring fits a drum or container *i*, preferably of perforated metal, constructed with a central aperture from which a sleeve *i'* extends upwardly, through which aperture and sleeve the shaft *d* passes. The latter 85 may be rotated at will so as to bring the desired articles contained in the drum *i* beneath the small trap *c*, by turning the hand wheel *k* on the horizontal shaft *l*, which rotates the shaft *d* by worm gearing. 90

Bottles may conveniently be held piled and radiating from the center of the carrier in racks provided by the vertical bars *m* rising from the rings *n*, which latter are preferably bolted or otherwise detachably 95 secured to the bottom of the drum *i*; the rack can then be easily removed if desired and fittings for other articles substituted.

o indicate boxes for ice, brine or other cooling element, or freezing mixture, located in the angles of the casing so as to surround the revoluble carrier, each of which boxes may have the usual drainage pipe such as *p*.

It is obvious that constructional details 105 may be varied very considerably without departing from my invention and I wish it to be understood that I do not confine or limit myself to the particular construction illustrated in the drawings.

What I claim and desire to secure by Letters Patent of the United States is:—

1. A cooling device including an upright casing having an opening in its top wall only, 5 a goods carrier horizontally revoluble in said casing, means within said casing for receiving a refrigerant to cool the goods on said goods carrier and a plurality of vertical bars on said carrier, said vertical bars being arranged in a plurality of concentric series adapted to receive bottles piled in contact horizontally and radiating with their heels only separated by the thickness of the vertical bars.
- 15 2. A cooling device including an upright casing having an opening in its top wall only, a goods carrier horizontally revoluble

in said casing, a plurality of concentric rings secured to the base of said carrier, means within said casing for receiving a refrigerant to cool the goods on said goods carrier and a plurality of vertical spaced bars carried by each of said rings, said bars being adapted to receive bottles piled in contact horizontally and radiating with their heels only separated by the thickness of the vertical bars. 20 25

In testimony whereof I have hereunto set my hand in the presence of two witnesses.

HAROLD HALE.
